UNITED STATES PATENT OFFICE

162,250

SQUEEGEE

Robert L. Staggers and Robert L. Warren,
Adairville, Ky.

Application August 23, 1950, Serial No. 11,890

Term of patent 14 years

(Cl. D9—2)

To all whom it may concern:

Be it known that we, Robert L. Warren and Robert L. Staggers, citizens of the United States, residing at Adairville, in the county of Logan and State of Kentucky, have invented a new, original, and ornamental Design for Squeegee, of which the following is a specification, reference being had to the accompanying drawing, forming a part thereof, wherein:

Fig. 1 is a perspective view of the squeegee embodying our new design; and

Fig. 2 is an end view of the squeegee shown in Fig. 1.

We claim:

The ornamental design for a squeegee, substantially as shown.

ROBERT L. STAGGERS.
ROBERT L. WARREN.
